UNITED STATES PATENT OFFICE.

WILLIE JAMES COLE, OF ABERDARE, WALES, ASSIGNOR TO THE BABCOCK & WILCOX COMPANY, OF BAYONNE, NEW JERSEY, A CORPORATION OF NEW JERSEY.

LINK FOR CHAIN-GRAVE STOKERS AND THE LIKE.

1,811,497.

Specification of Letters Patent. Patented July 29, 1919.

Application filed March 30, 1917. Serial No. 158,512.

To all whom it may concern:

Be it known that I, WILLIE JAMES COLE, a subject of the King of England, residing in Aberaman, Aberdare, South Wales, Great Britain, have invented certain new and useful Improvements in Links for Chain-Grate Stokers and the like, of which the following is a specification.

This invention is for improvements in or 10 relating to links for chain-grate stokers and the like and has for its object to provide an improved construction of link which has several advantages over the links now in use, such advantages being hereinafter set forth.

15 The links are secured together in the ordinary way by joint-pins which connect two links end to end; by making the joint-pins of any desired length, a series of such rows, side by side, may be built up to give any 20 desired area of chain-grate. The links are all joined up to give an endless band which is carried on two suitable revolving supports in the usual manner to provide for the feeding movement of the grate.

25 According to the present invention there is provided for a link in a chain-grate stoker the combination with a flat fuel-receiving plate, of lugs for the joint-pins depending from the ends thereof and so spaced apart as 30 to provide an air-pocket or box on the underside of the link.

According to another feature of the invention a link comprises a central lug at one end and opposed side lugs at the other end 35 adapted to receive between them the central lug of the next link, and a flange which forms a continuation of the central lug and connects it to the side lugs.

In the preferred construction the link as 40 above described is made in two parts being divided on a central longitudinal plane parallel with the planes of the lugs, such division therefore extending through the flange and central lug above mentioned.

45 In the accompanying drawings which illustrate a specific construction of link according to this invention—

Figure 1 is a side view showing one link and a portion of an adjacent link;

50 Fig. 2 is a plan of Fig. 1 looking from the underside, and

Fig. 3 is a perspective view of a complete link.

Like reference characters indicate like 55 parts throughout the drawings.

The link as above described is preferably made in two parts, but since the two parts together form one element of the chain, it will be described as if made in one part. The link comprises a plate A having a flat 60 upper surface A¹ which is adapted to receive the fuel in the furnace. At one end of this flat plate there is provided a lug B extending downward and centrally situated with respect to the width of the plate. This 65 lug is bored transversely at B¹ to receive a joint-pin, and extends beyond the end of the plate A. It is formed of a circular shape, as is shown most clearly in Figs. 1 and 3, the circle being such that the upper surface 70 A¹ of the plate A is tangential to it. The plate A is cut away at A² on its under side to continue the circle of the lug B and accommodate the lugs on the next link, as 75 hereinafter described.

At the other end of the plate A there are provided two lugs C D, one at each side of the plate and opposite one another. These lugs are circular like the lug B and are bored at C¹ D¹ respectively to receive a 80 joint-pin. The lugs C and D are spaced apart, as shown in Figs. 2 and 3, to provide a gap E between them, into which the single central lug B of the next link can enter.

A central flange F depends from the under side of the plate A in line with the lug B and preferably it is of the same thickness as this lug. This flange F extends along the under side of the plate A and is provided with side extensions F¹ F² which connect it 90 to the lugs C and D respectively.

The lower edge F³ of the flange F is curved inward, as shown most clearly in Fig. 1, this curve meeting the circular contours of the lug at each end smoothly. The 95 purpose of this shaping is to provide a bearing surface which will fit on a cylindrical carrying drum mounted at each end of the grate, thus rendering it unnecessary to provide drums of a pentagon or other flat-sided 100 shape, as has usually been the case.

When a number of links are assembled to form a chain, the central lug B of any one link has the two side lugs C D of the next link situated one on each side of it. The 105 ends C² of these side lugs constitute an end wall of a pocket on the under side of the link, as shown in Fig. 1. The other walls of the pocket are constituted by the vertical flange F and the lateral extensions F¹ F² 110

2
of the flange and the top plate A. Referring to Fig. 3, it will be seen that the surface F⁴ of the side flange F¹ constitutes one wall of the pocket of the link and the under surface A³ of the plate A constitutes another wall.

One such box or pocket is therefore formed on each side of the link, and when a number of links are assembled side by side, 10 each pocket lies opposite a similar box on the under side of the laterally adjacent link so that the two pockets together form a pocket which is open only on the under side. It will be seen that these pockets are 15 obtained by suitably spacing apart the lug B from the lugs C D on each link.

The vertical sides of the link are grooved or fluted as at G, to provide the requisite 20 passages for the admission of air to the fuel on top of the grate.

A hole F⁵ may be provided in the flange F of each link to permit lateral displacement of any coal which may fall on the chain when inverted; the teeth of the 25 sprockets whereby the chain is driven will then displace such coal laterally and binding of the teeth by such collections of coal is thus prevented.

While the link has been described as made 30 in one piece, it will be seen that according to the illustration it is divided longitudinally on the line H for simplicity in manufacture. The surfaces which abut one 35 another on the line H are fluted at H¹ similarly to the flutes G for the same purpose.

Among the advantages of this construction of the link it may be noted that the box-construction enables air to be supplied uniformly all over the grate so that individual 40 links do not get overheated. The circular shape of the lugs and the way in which they are fitted together in an undercut portion of the fuel-receiving plate, prevent any gaps being created as the chain passes around its 45 supporting drums. The link is particularly simple in its construction and cheap to manufacture; this is especially the case when each link is made in two parts, and by using duplicates of these two parts any 50 desired width of chain may be built up, no special links being required at any part of the chain. The links are such that they can be fitted to practically any chain-grate mechanical stoker and they impart to it the 55 special advantages obtained by their construction without detracting from other advantages which the general construction of the stoker may possess.

Another advantage of the box-construction 60 is that the driving member, by entering the box and operating on the lugs constituting one end of the box, in the direction indicated by the arrow J, Fig. 1, exerts only a compressive stress on the links instead of 65 tension. This renders it possible to use links

of a smaller section than is required when the driving force puts the links in tension, and, moreover, renders unnecessary the provision of special links or series of links in the grate for taking the drive from the 70 sprockets.

Finally, it may be noted that the openings in the fuel-receiving surface of the stoker consist practically only of the flutings on the vertical edges of the links and can therefore be prearranged as to their size. No 75 large openings are caused at any time and the amount of fuel lost by dropping through the grate is reduced to a minimum as compared with other types of link.

It will be understood that various modifications may be made in the precise details of construction of the link hereinbefore described. Thus, for example, the link illustrated may be made all in one piece instead 80 of in two pieces, and alternatively it may be formed so that the air-pockets are each contained wholly in one link instead of being a half in each of two adjacent links. The latter form, however, is preferred as it provides a more satisfactory means of supplying 85 air to the fuel.

What I claim as my invention and desire to secure by Letters Patent is:—

1. A link for a chain-grate stoker comprising a flat fuel-receiving plate formed with a centrally-disposed depending lug at one end, opposed side lugs at the other end, and a flange forming a continuation of the central lug and connecting it to the said 95 side lugs, said flange being provided with a transverse aperture adjacent the fuel-receiving plate.

2. A link for a chain-grate stoker comprising a flat fuel-receiving plate formed 105 with depending lugs so spaced apart as to provide an air-pocket on the underside of said plate, and a centrally-disposed flange connecting said lugs, the edge of said lugs and of said flange remote from the flat plate 110 being formed with a concave curve, substantially as set forth.

3. In a chain-grate stoker the combination of, links each comprising a flat fuel-receiving plate formed with a centrally-disposed 115 depending lug at one end, opposed side lugs at the other end and a centrally-disposed flange connecting said central lug to said side lugs, said flange being formed with a transverse aperture adjacent said fuel-receiving plate and the edge of the lugs and flange remote from the flat plate being formed with a concave curve, said links being provided with flutings on the vertical 120 surfaces thereof.

4. A link for a chain-grate stoker comprising a flat fuel-receiving plate formed with a centrally-disposed depending lug at one end, opposed side lugs at the other end and a central flange connecting said central 125

lug to said side lugs, said link being formed in two parts being divided on a central longitudinal plane parallel with the planes of the lugs, all the vertical faces of the link 5 being provided with flutings, substantially as set forth.

5. A bar link for a chain grate stoker comprising in combination a flat fuel receiving plate, a central longitudinal flange 10 depending from the middle of the underside of the said plate and also continued beyond it as one end of the link and in the form of a central semi-circular lug formed with a transverse hole adapted to receive a joint pin 15 and which is of a depth that is the maximum depth of the link, and two lugs at the other end of the longitudinal flange formed with transverse holes adapted to receive a joint pin, and consisting of two depending 20 side portions of the aforesaid plate lying at their inner ends against the opposite sides of said central flange and overlapping only a portion thereof, said depending lugs extending beyond the central flange as semi-circular lugs forming an end of the link, the 25 opposed faces of said lugs being parallel and spaced apart to form a flat-sided jaw whose vertical dimension is the maximum depth of the link and whose cavity is of such size 30 and shape as to receive the central lug of a similar companion link.

6. A bar link for a chain grate stoker comprising in combination a flat fuel receiving plate, a central longitudinal flange 35 depending from the middle of the underside of the said plate and also continued beyond it as one end of the link and in the form of a central semi-circular lug formed with a transverse hole adapted to receive a joint 40 pin and which is of a depth that is the maximum depth of the link, the bottom of said central flange being formed with a concave curve, and two lugs at the other end of the longitudinal flange formed with transverse 45 holes adapted to receive a joint pin, and consisting of two depending side portions of the aforesaid plate lying at their inner

ends against the opposite sides of said central flange and overlapping only a portion thereof, said depending lugs extending beyond the central flange as semi-circular lugs forming an end of the link, the opposed faces of said lugs being parallel and spaced apart to form a flat-sided jaw whose vertical dimension is the maximum depth of the link 50 and whose cavity is of such size and shape as to receive the central lug of a similar companion link.

7. A bar link for a chain grate stoker comprising in combination a flat fuel receiving plate, a central longitudinal flange depending from the middle of the underside of the said plate and also continued beyond it as one end of the link and in the form of a central semi-circular lug formed with a transverse hole adapted to receive a joint 60 pin and which is of a depth that is the maximum depth of the link, and two lugs at the other end of the longitudinal flange formed with transverse holes adapted to receive a joint pin, and consisting of two depending 65 side portions of the aforesaid plate lying at their inner ends against the opposite sides of said central flange and overlapping only a portion thereof, said depending lugs extending beyond the central flange as semi-circular lugs forming an end of the link, the opposed faces of said lugs being parallel and spaced apart to form a flat-sided jaw whose vertical dimension is the maximum depth of the link 70 and whose cavity is of such size and shape as to receive the central lug of a similar companion link.

In testimony whereof I have signed my name to this specification in the presence of two subscribing witnesses.

WILLIE JAMES COLE.
